UNITED STATES PATENT OFFICE.

JOHN E. GREENAWALT, OF DENVER, COLORADO.

CHARGE-CAR.

1,212,629.

Specification of Letters Patent. Patented Jan. 16, 1917.

Application filed August 5, 1914. Serial No. 855,183.

To all whom it may concern:

Be it known that I, JOHN E. GREENAWALT, a citizen of the United States, residing at Denver, in the county of Denver and State of Colorado, have invented certain new and useful Improvements in Charge-Cars, of which the following is a full, clear, and exact description, reference being had to the accompanying drawings, forming a part hereof.

My invention has relation to improvements in charge-cars; and it consists in the novel features of construction more fully set forth in the specification and pointed out in the claims.

In the drawings, Figure 1 is a side elevation of the charge-car with the controlling gates in closed position, parts being broken away; Fig. 2 is a vertical middle cross-section on the line 2—2 of Fig. 4, the gates being shown closed; Fig. 3 is a similar section, with the gates however shown in open position, and with the leveling plate depressed; Fig. 4 is a top plan of the car, parts being broken away; Fig. 5 is a rear elevation, or a view looking toward the bedding hopper, parts being in section; Fig. 6 is a vertical sectional detail on the line 6—6 of Fig. 1; Fig. 7 is a longitudinal sectional detail of the eccentric which controls the shaft of the delivery drum of the bedding material, the shaft being shown in elevation; Fig. 8 is a cross-section on the line 8—8 of Fig. 7, said figure likewise illustrating the friction pulleys diagrammatically; and Fig. 9 is a horizontal sectional detail on the line 9—9 of Fig. 2.

The present invention is an improvement on the structure of the traveling charge-car covered by U. S. Letters-Patent numbered 1,104,491, issued to me under date of July 21, 1914; and while contemplating the several objects and possessing the various advantages of the patented construction, the invention herein is characterized by structural details which insure for the material charged into, and deposited in, the pan or container in which said material is to be treated, a smooth, even and compact upper surface, the homogeneous character of which makes it possible to secure a simultaneous ignition of the entire surface of the charge

exposed to the igniting flame. This simultaneous ignition of the surface of the charge is an important factor, as without it the zone of combustion through the mass (so desirable to secure a homogeneous product) is practically impossible.

Another object of the present improvement is to secure an even deposit of the bedding or coarse non-agglomerating porous layer on which the charge proper is spread, the thickness of such bottom layer being directly controlled by the speed or rate of advance of the car across the pan receiving the charge.

A further object is to provide structural features, the advantages of which will be fully apparent from a detailed description of the invention, which is as follows.

Referring to the drawings, 1 represents a pan or treatment receptacle which in practice may be of any convenient size, the same as in my patent aforesaid, the pan being provided with grates G which collectively form the perforated bottom or support for the charge of material m (usually fines) to be treated or sintered as well understood in the art. The pan or receptacle is provided with hollow trunnions 2 disposed below the grates 80 and the charge supported thereon, and in free communication with the chamber 3 between the grates and the bottom of the pan. The trunnions communicate with a suitable exhauster or fan (not shown) whereby a partial vacuum is maintained in the chamber 3 during the sintering or roasting operation, or other treatment to which the charge may be subjected while in the pan, as fully described in my patent aforesaid.

Disposed adjacent the sides of the pan are rails R for the support of the wheels 4 of the truck T of the charge-car, said truck having mounted thereon the front charge hopper or holder H, and the rear bedding hopper or holder H'. The truck is built of any suitable structural members, and the hoppers are made preferably of quarter inch boiler plate properly riveted together and reinforced wherever necessary, these features falling within the purview of the skilled mechanic. To relieve the pressure on the walls of the hoppers, the latter are preferably provided with vertical partitions a, a, which di-

vide the respective hoppers into contiguous compartments for receiving the charges, the hopper H being filled with the charge of material (fines) m to be treated, and the hopper H' being filled with coarse non-agglomerating material m' which forms the previous bedding for the charge m , a layer of the bedding being first deposited and spread on the grates G. The truck T is preferably electrically propelled being provided with proper equipment for that purpose, that is to say with a controller C, a motor M, a reducer S, clutch-controlled gearing D, all well understood in the art and shown herein more or less conventionally. By a proper manipulation of the controller and gearing, the truck T may be propelled along the rails R first in one direction and then in the opposite direction according to the service to be performed by the hoppers and their coöperating elements to be presently referred to.

The discharge opening o of the bedding hopper H' is controlled by a hinged gate 5 secured to a rock-shaft 5' trunnioned between the sides of the truck frame T, the rock-shaft and gate being operated by hand levers or arms 6, 6, which oscillate along the curved plates or quadrants 7 secured to the hopper sides, said quadrants being provided with a series of holes or openings h with any one of which a corresponding hole or opening in the hand-lever may be brought into register, and a locking pin or eye-bolt 8, carried by a chain 9 fastened to the lever, inserted through said registering openings. In this way the gate 5 may be swung open to any degree or through any desired angle and locked in position by the pin 8. The bedding material m' discharged from the hopper H' is directed out of the hopper and properly distributed along the depository surface of the pan (that is to say along the upper surface of the grates G) by a drum 10 disposed about a shaft 11, said shaft being disposed parallel to the axle A of the rear pair of truck-wheels 4, 4, and supported in bearings 12, 13, the former (12) being any conventional form of bearing which will permit of a slight oscillation of the shaft 11 for a purpose presently to appear. The bearing 13 carries an eccentric 14 through which the shaft 11 directly passes, said eccentric being provided with a lever arm 15. By oscillating the lever arm a rotation is imparted to the eccentric 14 and hence a slight oscillation is imparted to the shaft 11 about the bearing 12 as a fulcrum. The end of the shaft 11 adjacent the bearing 13 carries a friction pulley 16 which, by a proper throw of the lever 15 may be brought into frictional engagement with the pulley 17 on the axle A. This engagement of course results from oscillating the shaft 11 toward the axle A with a rocking of the eccentric 14 in proper direction by means of the lever 15, a

disengagement between the pulleys being effected by a throw of the eccentric lever rocking the eccentric in the opposite direction. The lever 15 is provided with a perforation for the insertion of a locking pin or eye bolt 18 secured to a chain 19 on the lever, the perforation referred to registering with one of a series of holes or openings h' formed in a plate 20 secured to the side of the truck frame T.

The front wall or inclined bottom e of the charge hopper H is fixed, and is disposed at a steep angle to insure proper discharge of the contents, said wall e extending below the lower edge of the opposite or rear wall of the hopper, the vertical side walls of the hopper terminating in bottom extensions or wings w , w , which reach down to within about an inch from the top edge of the pan 1, and bound or confine between them, the lower portion of the wall e . The lower edge x of the wall e (which is substantially even with the lower edges of the wings w) may serve as a cutting edge for the discharged material as presently to more fully appear. The discharge mouth or opening O of the charge hopper H is normally closed by a hinged door or gate 21, said door being secured at each end to lever angle-bars 22, 22, disposed in pairs, each pair having riveted thereto at an intermediate point a lug or arm 23 which is pivotally mounted between pairs of brackets 24, 24, secured along the rear wall of the hopper H, a hinge pin 25 being passed through registering openings in the parts 23, 24. A stiffener bar in the form of an angle-bar 21' secured to the levers 22 serves to reinforce the free edge of the door or that most subjected to the abrading action of the charge. When the gate or door 21 is closed, the levers 22 (which are slightly bent in the plane of their oscillation) assume the position shown in Fig. 2, the upper ends being held away from the rear wall of the charge hopper by the toggle-links 26, 27, the shorter link being hinged to the member 27 and its corresponding pair of levers 22, and the fixed ends of the links 27 being formed with bosses d which are secured to a rock-shaft 28 to one end of which is keyed an operating lever 29. When the lever is oscillated to the position indicated in Fig. 1, the shaft 28 is rocked in proper direction to straighten out the toggle formed by the links 26, 27, this action driving the upper ends of the levers 22 from the rear wall of the charge-hopper, and causing the door 21 to oscillate toward the hopper and close the mouth O thereof (Fig. 2). The door when thus swung to a closed position locks automatically under the action of the toggle, the straightening of the links 26, 27, insuring a positive lock. To unlock and open the door, the lever 29 is rocked in the opposite direction, thus "breaking" 130

or closing the toggle (Fig. 3) when the door readily swings to open position, the same swinging freely about the hinge-pins 25, and yielding to the weight and pressure of the material released from the charge hopper. In its oscillations the door 21 operates between the wings w , w , so that none of the charge can escape from the sides of the hopper, every particle of the material being directed into the pan 1 above which the car travels. The door 21 likewise operates on one side of the inclined wall e and below the bottom edge of the rear wall as obvious from the drawings.

15 Mounted between the wings w , w , in front of and adjacent the wall e of the charge hopper and slightly above the lower edge x of said wall and on the side of the wall opposite from the gate 21, is a trunnioned rock-20 shaft or rocker-bar 30 to one of whose terminal trunnions is keyed, or otherwise secured, an operating lever 31, the lever being spanned by a bracket or yoke 32 secured to the track frame T. The lever may be 25 locked in either one of its limiting positions by a pin 33 carried by a chain 34 secured to the bracket, the pin being passed through one of the openings h'' in the bracket and an opening in the lever registering there-30 with when the lever is swung through the necessary arc to effect such registry. To the rocker-bar 30 is secured a leveling plate or follower 35 whose free edge (that is to say, the edge farthest from the wall e), is pro-35 vided with an angle-bar stiffener 36, the plate extending forward a suitable distance beyond the front vertical edges of the wings w , w . The inner or rear edge x' of the lev-40 eling plate is ordinarily at substantially the same level with the edge x of the wall e (Figs. 2, 3,) in which case the edge x alone acts as a cutting edge; where the edge x is higher than the edge x' , then both edges serve as cutting edges. In practice, how-45 ever, it is better not to have the edge x higher than the edge x' , for where both edges serve as cutting edges more material must be leveled and pressed down into the pan by the front edge of the plate 35, than 50 is the case where a single cutting edge is used. In the present embodiment of my in-vention the leveling plate 35 is entirely out of range of the path of discharge of the material from the hopper H, the free or 55 front oscillating edge of the plate being lifted about an inch or three quarters of an inch above the edge of the pan when the plate is in its raised position (Figs. 1, 2). When fully depressed (Fig. 3) the 60 free edge of the plate is substantially on a level with the top edge of the pan, so that the material which projects above the top edge of the pan upon discharge thereof into the pan from the hopper H, will not 65 only be leveled by the plate but be smoothed

down, and compacted into the pan leaving the upper crust of the charge in the pan in an ideal condition for subsequent ignition. In its depressed position, the plate 35 is disposed at a flat or acute angle to the plane 70 of the upper surface of the charge, whereby during the leveling operation, advancing as it does across the pan rearwardly (to the right in Fig. 3) it acts as a trowel, not only smoothing the material but in a measure 75 compacting it.

The operation will now be readily understood, and is substantially as follows: Assuming that the hoppers H, H', are filled with their respective materials m , m' , the 80 operator (riding on the car) starts the motor M in a given direction, thereby propelling the car forward (to the left in Fig. 3), the pan 1 being of course under the car. The operator thereupon opens the gate 5 the 85 necessary degree, uncovering the discharge opening o which allows the bedding m' to discharge over the drum 10. Rotation in proper direction is imparted to the drum by causing engagement between the friction 90 pulleys 16, 17, this being accomplished by a throw of the eccentric 15 in proper direction (Fig. 8) as already explained. The rotating drum 10 delivers a stream of material m' of a given thickness (Fig. 3), but 95 in being spread over the grates G, this thickness is reduced by substantially one-half. It will be seen that the pulley 17 which receives its rotation from the axle A of the rear wheels 4 has a diameter of substan-100 tially one-half that of the pulley 16, so that the car travels a distance corresponding to two revolutions of the pulley 17 while the pulley 16 makes but one revolution. It follows therefore that the stream delivered by 105 the drum 10 which rotates conjointly with the pulley 16, will be spread over an area whose dimension in the line of travel of the car is represented by two revolutions or circumferences of the rear wheels 4, and since, 110 during this travel, the drum 10 makes but one revolution, the stream spread over the grates and which forms the coarse bedding for the charge will be about one half the thickness at which it is delivered to the 115 drum. Thus, and for example, assuming the opening o to be two inches wide, and assuming that the peripheral speed of the drum 10 is about one half the speed of the car, the two inch stream will be reduced to a one 120 inch layer when finally spread over the grates G. The thickness of the bedding is therefore determined by the gear ratio between the car axle or running gear and the feed or delivery drum 10. In the present embodiment of my invention, the porous bedding is preferably deposited on the grates before the charge proper is admitted into the pan, so as to give the workman an 125 opportunity to see that all parts of the 130

grates are thoroughly covered. I do not however, wish to be restricted to this preferred method of operation.

The bedding being spread upon the grates 5 (by a passage of the car across the pan) the operator now reverses the motor causing the car to travel in the opposite direction (to the right in Fig. 3). At the same time he opens the gate 21 by throwing the lever 29 10 in proper direction to "break" the toggle 26, 27, whereupon the contents of the hopper A is discharged through the mouth O into the pan on top of the bedding. As the car advances the edge α (or edges α , α' , as described) will serve as a cutting edge for the discharged material, the operator at the same time depressing the plate 35 (and locking the same in said depressed position) as 15 already described, said plate leveling and compacting the upper layers of the charge to a plane substantially even with the upper edge of the pan. Thus leveled and compacted, the charge is in an ideal condition for ignition and subsequent roasting, sinter-roasting, or other treatment well understood in the art.

I may of course depart from the structural details of the charge-car here shown. The truck part T might be otherwise constructed, a different type of motor might be used, different means for operating the doors might be improvised, and other changes made without departing from the spirit of my invention. The terms "front" 30 and "rear" as used herein are merely for convenience. Thus, the "front" wall e of the hopper H might be considered the rear wall depending on which end we choose to regard the front of the machine. It is here termed "front" because the car is regarded as advancing forward during the deposit of the bedding layer m' on the grates, and rearward or backward during the deposit of the charge m over the bedding m' . In this 35 latter operation the front or free edge of the follower plate or leveler 35 follows the hopper H, and the cutting edge α , this constituting a feature not present in the charge-car forming the subject-matter of my patent 40 aforesaid. In the present construction the wall e operates as a partition between the leveler 35 and the charge-supporting door or gate 21, the parts 35 and 21 being disposed on opposite sides of said wall e . In 45 lieu of the reducing gear 16, 17, interposed between the running gear of the car and the drum 10, it is obvious that other gearing may be substituted, so as to obtain any desired relation between the peripheral speed 50 of the drum and the travel of the car in any unit of time. In this way the thickness of the sheet of bedding m' deposited on the grates G may be varied to suit conditions. 55 We might for example employ speed or multiplying gears so as to increase the

peripheral rate of travel of the drum, thereby spreading a sheet thicker than the width of the discharge opening o .

It will be observed (Fig. 3) that the door 21 is so pivoted or hinged, that in its oscillations the free edge thereof does not drop materially below the bottom edges of the wings w , w , (Fig. 3). This permits the door to clear the pan and allows the car to be run past the pan when the latter is filled, without danger of the door fouling any portion of the pan. The leveler 35 of course passes off the edge of the pan as the car travels along the rails R. The present charge-car therefore contains a cutting element (α , or α' ,) and a leveling and compressing element (35 or its equivalent) the former element cutting off the charge at a definite level as it is delivered from the hopper H, and the latter element leveling and compressing the same. The edge α in the present instance is the lower edge of the wall e of the charge hopper, but it need not necessarily be a part of the hopper to serve its function as a cut-off. It will be noted that the element α (or its equivalent) cuts off or levels the charge to a certain level, and the element 35 (or its equivalent) compresses and levels the charge to a lower level. This feature I consider new, and in practice it has decided advantages, the charge not only being deposited uniformly, but after the leveler 35 passes over the same, the charge is left as smooth and true as the top of a table.

Having described my invention, what I claim is:—

1. In a traveling charge-car, a holder having inclosing walls and open at the bottom, a movable gate disposed across said open bottom on one side of one of the inclosing walls aforesaid for supporting the charge in the holder, and a movable member on the opposite side of said wall operating to be depressed below the bottom edge of said wall and below the level of the discharged material cut off by said edge whereby said member may serve as a leveler.

2. In a traveling charge-car, a holder having inclosing walls and open at the bottom, a movable gate disposed across said open bottom on one side of one of the inclosing walls aforesaid for supporting the charge in the holder, and an oscillating member on the opposite side of said wall adapted to be depressed below the lower or bottom edge of said wall whereby said member may serve as a leveler.

3. In a traveling charge-car, a holder having inclosing walls and open at the bottom, a movable gate disposed across said open bottom on one side of one of the inclosing walls aforesaid for supporting the charge in the holder, and an oscillating member disposed on the opposite side of said wall out of range of the path of discharge of the ma-

terial, and adapted to be depressed below the bottom edge of said wall, and below the level of the discharged material cut off by said edge, whereby said member may serve 5 as a leveler.

4. In a traveling charge-car, a holder having inclosing walls and open at the bottom, a movable gate disposed across said open bottom on one side of one of the inclosing 10 walls aforesaid for supporting the charge in the holder, an oscillating member having its axis of rotation disposed on the opposite side of said wall and between said wall and the free edge of the member, said free edge 15 operating to be depressed below the bottom edge of said wall and below the discharged material cut off by said edge, whereby the bottom edge of the wall serves as a cutting edge and the depressed member 20 serves as a leveler with a travel of the car in proper direction.

5. In a traveling charge-car, a holder for the charge, a door or gate supporting the charge in the holder for a closed position of 25 the gate and releasing the charge with an opening of the gate, and means on the car outside the holder and positioned out of range of the path of discharge from the holder, for leveling the discharged material 30 along a plane depressed below the level of the discharged material cut off by the passage of the car thereover.

6. In combination with a treatment receptacle, a charge-car provided with a 35 holder disposed in movable relation to the receptacle and adapted to discharge thereinto, and a movable member on the car operating to be depressed below the bottom of the holder and at an acute angle to and below 40 the plane of, the upper surface of the material deposited in the receptacle for leveling the same.

7. In combination with a treatment receptacle, a charge-car provided with a holder 45 disposed in movable relation to the receptacle and adapted to discharge thereinto, and an oscillating plate on the car operating to be depressed below the bottom of the holder and at a flat angle to and below the plane of, 50 the upper surface of the deposit in the pan, for leveling the material so deposited.

8. In a traveling charge-car, a holder provided with a bottom cutting edge, and a leveling member adapted to follow and be 55 depressed below said edge.

9. In a traveling charge-car, a holder having a wall terminating at the bottom in a cutting edge, and a movable leveling member depressed below, and following said 60 edge in the travel of the car in proper direction.

10. In a traveling charge-car provided with running gear, a suitable holder for the material, means for effecting a discharge of 65 said material with a travel of the car in a

given direction, means for spreading the material so discharged, and suitable gearing interposed between the running gear and the spreading means for determining the thickness of the layer so spread. 70

11. In a traveling charge-car, a suitable holder for the material, means for releasing the contents of the holder, a rotating drum for spreading the material in sheet form after its release, suitable reducing gear interposed between the drum and running gear of the car for reducing the peripheral speed of the drum relatively to the distance traveled by the car in a unit of time, whereby the thickness of the sheet may be predetermined, and means for disengaging the drum from said running gear. 75

12. A charge-car having an open-bottomed holder comprising side parallel walls, a rear wall and a front inclined wall terminating at the bottom below the bottom of the rear wall, extensions leading from the side walls and bounding the lower portion of the inclined wall, a gate operating between the side extensions on one side of the 85 inclined wall and below the bottom of the rear wall for closing the open bottom of the holder and thereby supporting the charge, and a movable member on the opposite side of the inclined wall operating between the 90 side extensions for leveling the contents of the holder to a plane below the level of the material as first discharged.

13. A charge-car having an open-bottomed holder comprising side parallel walls, 100 a rear wall, and a front inclined wall terminating at the bottom below the bottom of the rear wall, wings or extensions leading from the side walls and bounding the lower portion of the inclined wall, a hinged gate 105 operating on one side of the inclined wall between the wings with its free edge maintained permanently above or not materially below the bottom edges of the wings, and an oscillating leveler plate mounted between the wings on the opposite side of the inclined wall, and operating to be depressed below the bottom edge of the inclined wall and below and to a flat angle with, the surface of the deposited charge to be leveled. 110

14. In an apparatus of the character described, a holder for the material operating to discharge the same into a suitable receptacle, means for cutting off the charge in said receptacle at a certain level, and means 115 for subsequently compressing the same to a different level.

15. In an apparatus of the character described, a holder for the material operating to discharge the same into a suitable receptacle, means for cutting off the charge in said receptacle at a certain level, and means 125 for subsequently compressing and leveling the same to a lower level.

16. In an apparatus of the character de- 130

scribed, a leveling cut-off member operating in a given plane, and a compressing member operating in a different plane.

17. In an apparatus of the character described, a leveling cut-off member operating in a given plane, and a compressing and leveling member operating in a lower plane.

18. In an apparatus of the character described, a fixed, leveling cut-off member

operating in a given plane, and a movable compressing and leveling member operating in a lower plane.

In testimony whereof I affix my signature in presence of two witnesses.

JOHN E. GREENAWALT.
